UNITED STATES PATENT OFFICE.

EMIL R. DRAVER, OF RICHMOND, INDIANA.

WINDOW-SASH HOLDER.

Application filed May 18, 1926. Serial No. 109,977.

This invention relates to a window sash holder. As is well known, it has been a common practice to counterbalance window sashes with weights which are disposed and move in the window casings, said weights being connected to the sash by cords and running over pulleys mounted in the casing. This equipment involves a great deal of special work and construction and the weights 10 are at the same time apt frequently to become disconnected.

It is an object of this invention, therefore, to provide a window sash holder adapted to hold the window sash in any position to 15 which it may be raised and yet it will not in any way interfere with the desired movements of the sash, and one which will eliminate the necessity for any weights, weight cords, weight boxes and pulleys.

It is a further object of the invention to 20 provide a window sash holder comprising resiliently acting means adapted to hold the sash in any position to which it may be raised, the sash being easily moved upward 25 and being movable downward with more resistance.

It is more specifically an object of the 30 invention to provide a window sash holder in the form of a sear spring secured to the sash and having a compressible and expandible portion disposed in a recess therein and having an arm adapted to move in contact with the window casing and adapted to hold the sash stationary in any desired position.

These and other objects and advantages 35 of the invention will be fully set forth in the following description made in connection with the accompanying drawing, in which like reference characters refer to 40 similar parts throughout the several views and in which:

Fig. 1 is a view in front elevation of a portion of a window casing and sash therein, showing the invention applied thereto, 45 certain parts being broken away and others shown in vertical section;

Fig. 2 is a horizontal section taken on line 2-2 of Fig. 1;

Fig. 3 is a perspective view of the sash 50 holder;

Fig. 4 is a view partly in front elevation

and partly in vertical section of a modified form of the device; and

Fig. 5 is a view in elevation as seen from the left of Fig. 4. 55

Referring to the drawings, a portion of a window casing is shown, comprising the inner member or stile strip 7 and the side member 8. The side member has adjacent its center the usual parting strip 9 between 60 the lower sash 10 and the upper sash 11 and is further shown as equipped with the outside bead 12 and the inside finishing strip or molding 13 which, with the parting bead 9, forms the guideway for the lower sash 65 10. The sash 10 is illustrated as having the usual pane 14 therein.

In accordance with the present invention, a recess or mortise 10^a is formed in one of the members 8 or 10 and while it is within 70 the scope of this invention to have the recess and sash holding means in either the casing or sash, in the embodiment of the invention illustrated, the recess 10^a is shown as formed in the sash 10. A member 15 is 75 provided, and while this member might be variously formed and of various styles of material, in the embodiment of the invention illustrated it is shown as formed from a flat spring plate of uniform width. The member 15 comprises a straight portion 15^a having an aperture 15^a adapted to receive the screw 16 which secures the member 15 to the sash 10. As shown in Fig. 2, the member 15 is secured to and set in the inner 80 edge of the sash 10 substantially centrally thereof. The member 15 also comprises a loop portion 15^b extending substantially at right angles to the portion 15^a and said loop portion has formed at one end an arm 15^c 85 projecting outwardly beyond the straight portion 15^a extending downwardly some distance and having its terminal end again curved inwardly.

It will be noted that the upper part of 95 the arm 15^c extends at a slight angle to the inner side of the member 8 and of the casing, while the lower portion of the arm 15^c which is bent inwardly, extends at a greater angle to the inner side of the member 8. As 100 shown in Fig. 1, the loop 15^b is disposed in the recess 10^a and said recess has a down-

wardly extending and narrower portion at the outer side of the sash in which the lower end of the arm 15^c is disposed. A screw 17 extends through the sash 10 from the inner side thereof having its threaded end in contact with the inner side of the member 15 and at the lower part of the portion 15^a. The screw 17 is provided with a grooved head which preferably will be disposed in a recess 10^b formed in the sash 10.

With the structure described, the arm 15^c bears against the inner side of the casing or member 8 with considerable friction. This friction is more than sufficient to sustain the weight of the sash 10. When the sash is raised upwardly, the arm 15^c slides along the inside of the member 8 and owing to the cam action against the member 8, said arm swings slightly downwardly, expanding the loop 15^b so that the arm 15^c also swings inwardly. This greatly relieves the friction against the member 8 so that the sash can be raised with very little friction between the arm 15^c and the casing 8. When the window sash tends to move downwardly, however, the friction of the arm 15^c against the casing tends to swing said arm upwardly. This acts to compress the loop 15^b and to raise said loop. It will be noted that the top of the loop is disposed substantially against the top of recess 10^a so that the loop cannot bodily be raised. As the arm 15^c swings upwardly and outwardly, it increases the friction on the member 8. The arm 15^c, however, will slide along the member 8 if sufficient force be applied to the window sash so that said sash can readily be pulled down and closed by merely exerting sufficient pressure thereon. As stated, the friction of arm 15^c against the casing 8 is more than sufficient to sustain the weight of the sash 10. As stated, the arm 15^c makes a more abrupt angle with the casing 8 at its lower portion, which gives a more decided cam action on the arm 15^c when the sash is lowered. The screw 17 may be adjusted from the inside of the sash to exert more pressure on the member 15 thus moving the same slightly outward. This will cause the arm 15^c to exert more pressure on the window casing so that the friction will be increased. This adjustment may be desirable to properly position the member 15 for light and heavy sashes. If desired, a pad of yielding material such as felt or rubber 18 may be disposed in the loop 15^b. This does not interfere with the action of the member 15 and tends to deaden the noise, if any, and to prevent any squeak or chatter of the member 15 when the sash is being moved.

In the embodiment shown in Figs. 4 and 5, a member 20 is provided having a cylindrical shank portion 20^a and an outer head or cam portion 20^b. The portion 20^b has a cylindrical portion extending inwardly

therefrom forming a shoulder 20^c. A coil compression spring 21 surrounds the shank 20^a bearing at one end against the shoulder 20^c and bearing at its other end against a washer 22. The members 20, 21 and 22 are disposed in a mortise or recess 23^a formed in the side of the sash 23. The recess 23^a has a reduced portion 23^b at its inner end forming a shoulder against which the washer 22 fits. It will be noted that the head 20^b has a curved outer surface of considerable width, the upper portion of which extends at quite a sharp angle to the inner side of the sash 23 and thus to the inner side of the casing. The lower portion of said surface of the head 20^b is curved inwardly at a much sharper angle to the inner side of the sash 23 and thus to the inner side of the casing. The upper end of the head 20^b is disposed in a small arm of the recess 23^a so that the head 20^b is prevented from turning about the axis of its shank 20^a.

In operation, when the sash 23 is raised, the upper portion of the head 20^b will slide along the inside of the casing and the head 20^b and member 20 will be moved inwardly of the sash, thus compressing the spring 21. The sash 23 can thus be raised with very little effort and with very little friction of the member 20 against the casing. When the sash is lowered, however, the lower portion of the surface on head 20^b acts against the side of the casing and tends to swing the member 20 upwardly. This causes the head 20^b to wedge or bind against the casing and sash. This action is more than sufficient normally to hold the sash in any position to which it is moved. If sufficient pressure, however, be exerted on the sash, it can be pulled down and the member 20 will move inwardly, thus compressing the spring 21 and permitting the sash to be lowered.

From the above description it is seen that applicant has provided an extremely simple and efficient window sash holder. The holder automatically sustains the sash in any position in which it is moved, permits the sash readily to be raised and does not interfere with the closing of the sash. The device eliminates the necessity of the cumbersome weights, cords, pulleys and the weight box which have heretofore commonly been used with the window structures. The device is extremely simple, comprises few parts and is very easily and quickly installed. The device can be placed on any ordinary sash and requires very little change therein. The device has been amply demonstrated in actual practice and found to be very successful and efficient.

It will, of course, be understood that various changes may be made in the form, details, arrangement and proportions of the parts, without departing from the scope of applicant's invention, which, generally

stated, consists in a device capable of carrying out the objects above set forth, in the novel parts and combinations of parts disclosed and defined in the appended claims.

5. What is claimed is:—

1. The combination with a window casing member and window sash member of a resiliently actuated means carried by one of said members having a portion engaged by the 10 other member permitting relative movement of said means and other member with little resistance when the sash is raised and having means acting on said portion permitting relative movement of said means and other 15 member with much greater resistance when said sash is lowered, said means normally engaging said other member with sufficient friction to sustain the weight of said sash.
2. The combination with a window casing 20 member and a window sash member of a resiliently movable device carried by one of said members having a portion engaging the other member frictionally to hold said sash in stationary position, said device having a 25 cam surface engaging said other member whereby when the sash is raised, said portion will be moved to decrease the friction so that said sash can easily be raised and also having a surface engaging said other member 30 so that when said sash is lowered, said portion will be swung to increase the friction.
3. The combination with a window casing and a window sash of a sear spring carried by one of said members and disposed in 35 a recess therein, having an arm adapted frictionally to engage the other of said members normally to hold the sash in any stationary position, said arm having a surface 40 at its upper portion inclined at an angle to said other member whereby when said sash is raised, said arm is swung to decrease the friction and having a surface extending at a greater angle to said other member 45 so that when said sash is lowered, said arm

is swung outward to increase the friction.

4. The combination with a window casing and a window sash of a flat spring carried in a recess in said sash, said spring being bent to have a compressible and expandable loop disposed in said recess and to have an arm projecting from said recess and adapted frictionally to engage the inner side of said casing, said arm normally holding said sash in stationary position, said arm having an 55 upper surface which, when the sash is raised, engages said casing to swing said arm inwardly and expand said loop and having a surface engaging said casing which, when the sash is lowered, swings said arm outwardly and compresses said loop whereby the friction is increased.

5. The combination with a window casing member and a window sash member of a spring device secured to one of said members, 60 having a substantially closed loop portion disposed in a recess in said member and having an arm connected to one end of said loop frictionally engaging the other member to hold the window sash member in any position to which it is raised but permitting up and down movement of said sash member.

6. The combination with a window casing and a window sash slidable therein, of a resilient device carried in a recess in one of said members and having a portion adapted frictionally to engage the other portion, said portion being formed with upper and lower surfaces, the upper surface engaging said other member to move said device to a releasing position whereby it will have little friction when the window is raised and the lower surface engaging said other member and moving said device to a wedging position when the window is lowered whereby said 75 portion will have increased friction and hold said members relatively stationary.

In testimony whereof I affix my signature.
